UNITED STATES PATENT OFFICE.

LERoy L. SALFISBERG, OF NEWARK, NEW JERSEY, ASSIGNOR TO IVERS-LEE COMPANY, OF NEWARK, NEW JERSEY, A CORPORATION OF DELAWARE.

FOLDING DEVICE.

Application filed November 10, 1920. Serial No. 423,046.

To all whom it may concern:

Be it known that I, LEROY L. SALFISBERG, a citizen of the United States, and a resident of Newark, in the county of Essex and State of New Jersey, have invented an Improvement in Folding Devices, of which the following is a specification.

The present invention relates to an improvement in folding devices for articles in strip form, such for example as packages containing a plurality of articles secured in a tubular container and spaced apart at suitable intervals. The folding device may form an integral part of a packaging machine adapted to make a package of the continuous strip type referred to, or it may be a separate unit.

One embodiment of my invention is illustrated in the drawings accompanying the present specification, and in which

Figure 1 is a front elevation,

Figure 2, a transverse vertical section on the line 2—2 of Figure 1,

Figure 3, an end elevation with the crimping apparatus removed,

Figure 4, a rear view with a portion of the housing and a portion of the crimping roll shafts in vertical section,

Figure 5, a detail in transverse vertical section showing the guide box for the folded package,

Figure 6, a fragmentary view illustrating the strippers meshing with the folding members, and

Figure 7, a detail view in transverse horizontal section illustrating a form of cutting-off device.

Referring now to Figure 1, the folding device of the present invention is shown positioned in operative relation to the discharge end of a packaging machine which includes a feeding arrangement comprising chains 1 and 2 actuated to move a package 3 of irregular shape in the direction indicated by the arrow. The package illustrated consists of a tubular paper container enclosing tablets, powders, or the like, said tablets being spaced apart by crimped portions, thus forming a continuous strip of enclosed articles, the portions of said strip which contain the tablets being relatively thick, while the intervening or crimped portions are relatively thin, being not more

than the combined thickness of the paper and adhesive material forming the tubular enclosing member. The crimping rollers 4 and 5 and a suitable severing device 6 preferably positioned in advance of said crimping members in the direction of movement of the strip and more clearly shown in Figures 3 and 7, form a part of the complete packaging machine.

Where the folding device is integral with the packaging machine or continuous with the operation thereof, it will be positioned in advance of the severing device, preferably as illustrated in Figure 1, and may comprise a pair of cooperating strip engaging and moving members 7 and 8 mounted on shafts 9 and 10 respectively, said shafts being geared together, as shown in Figure 2, and driven by means of a gear 11 actuated from any suitable source of power, preferably the driving mechanism of the package forming machine. The members 7 and 8 are of the same construction and each consists of a plurality of radial arms 12, the free end of each arm having at its forward part a curved article engaging surface 13 and a rearward angular terminal portion 14. The article engaging and moving members are also preferably slotted as indicated in Figure 2, said slots being proportioned and positioned to receive striping members 15 (Figure 6), mounted in the framework of the machine, their inner surfaces forming the upper and lower surfaces respectively of the receiving end of a package guiding box portion 16, having at one side a resilient member 17 (Figure 5) adapted to exert yielding lateral pressure on the folded article as it is pushed forward through the box 16.

Where the folding device forms a part of the packaging machine, it is desirable to have the folder actuating shafts 9 and 10 geared in synchronism with the crimping and severing mechanism. Thus, referring to Figure 3, the knife 6 is operated by a cam 18 mounted on a shaft 19, said cam cooperating with a bell crank lever 20 having at its free end a rack 21 engaging a pinion 22 loosely mounted on a hub 23 of a slotted plate 24, said plate being securely attached to a slidable bolt 25 mounted in a recess in the framework of the machine

and holding a stationary cutter member 26 yieldingly through a spring 27 against the knife blade 6 which is secured to the pinion 22 and oscillates therewith. The plate 24 is prevented from rotating by a detent 35, (Figure 3), extending into a corresponding notch in the periphery of the plate. The shaft 10 also carries a gear 28 actuated by intermediate gearing with the shaft 19 which drives the severing mechanism. Thus, when it is desired to readjust the machine so as to sever strips containing a different number of units, the connecting gearing between the crimping mechanism on the one hand and the folding and the severing devices on the other will be changed. In other words, assuming that the machine with a given crimping rate and spacing is operating in such a manner as to cut strips of 12 units each and it is desired to adjust the machine so that it will cut strips of 20 units each, a proper adjustment of the gearing connecting the crimping mechanism with the severing and the folding devices must be made.

In operation the strip 3, after passing the severing device advances into engagement with the folding members which are so positioned with relation to each other that the rounded end of the strip engaging arms 11 will engage the article containing portions of said strip with a wiping contact, at the same time pushing said portions forward and beyond into the package guiding box 16. The angular end 14 of each of the folding members engages the strip at a thin portion and the distance between said angular end of a strip engaging arm and a relatively flat portion of an adjacent arm on the other folding member is sufficient to accommodate the thin portion of the strip without deforming or injuring it. Similarly, the distance between the rounded or wiping face of a strip engaging arm of one member and a relatively flat face of an adjacent arm of the other member will be sufficient to accommodate a filled portion of the container without crushing or injuring the article contained. When the parts are properly positioned and synchronized as described, the package in strip form will be bent by the folding mechanism across an empty or crimped portion thereof preferably adjacent to a filled portion. This permits the formation of a package with the enclosed articles in zigzag arrangement.

In order that the operator may more readily have access to the folders, a portion 29 of the housing is hinged at 30 and 31, said portion 29 having a small projection 32 extending rearwardly and engaging a spring pressed detent 33 which serves to hold said portion 29 normally in folder protecting or covering position. It is clear that, by pulling down on the thumb-piece 34, the spring

holding the shaft 33 will be compressed and the portion 29 will swing forward and downward so as to give access to the folders for adjustment or other manipulation.

I claim as my invention:

1. A folding device for articles in strip form and having alternating relatively thick and thin portions, comprising cooperating rotatable members having radial arms, each arm having a rounded face for engaging the relatively thick portions of the article and moving the same and an angular end engaging the relatively thin portions of the article and cooperating with the rounded face to effect transverse bending of said article. 70

2. A folding device for articles in strip form and having alternating relatively thick and thin portions, comprising cooperating rotatable members having radial arms, each arm having a surface positioned and adapted for wiping engagement with the relatively thick portions of the article to move the same and an angular end engaging the relatively thin portions of the article and cooperating with said wiping surface to effect transverse bending of said article. 85

3. A folding device for articles in strip form comprising the rotatable article engaging members 7 and 8 having radial arms each provided with the rounded portion 13, 95 said rounded portions of one member cooperating with the relatively straight portions 12 of the other member to move the article by predetermined increments and to bend said article transversely. 100

4. A folding device for articles in strip form comprising a pair of rotatable article engaging elements mounted on spaced shafts, each element comprising a plurality of article engaging radial arms having parallel longitudinal slots, article guiding and stripping members operatively engaging said slots, and means for rotating the article engaging elements simultaneously. 105

5. A folding device for articles in strip form comprising cooperating article engaging members for moving and bending the article, said members each including a plurality of radial arms rounded on their forward ends to engage the article with a wiping contact, the members being rotatably mounted on spaced shafts, and means in the path of the bent strip or article to guide the same and to exert yielding resistance to the movement thereof. 110

6. A folding device for articles in strip form comprising a pair of rotatable cooperating elements provided with article bending and moving arms each having a forward article engaging face of different contour 125 from its rearward article engaging face.

7. A folding device for articles in strip form comprising a pair of rotatable cooperating elements provided with article bending and moving arms each having a forward ar-

ticle engaging face of curved contour and a rearward article engaging face of a contour different from that of the forward face.

8. A folding device for articles in strip form comprising a pair of rotatable cooperating elements provided with article bending and moving arms each having a forward

article engaging face of curved contour and a flat rearward article engaging face.

In testimony whereof, I have signed my name to this specification this 29th day of October 1920.

LEROY L. SALFISBERG,
